UNITED STATES PATENT OFFICE.

JOSEPH J. BRENK, OF MILWAUKEE, WISCONSIN, ASSIGNOR OF ONE-HALF
TO HAROLD G. UNDERWOOD, OF SAME PLACE.

MATCH-SAFE.

SPECIFICATION forming part of Letters Patent No. 506,303, dated October 10, 1893.

Application filed January 19, 1892, Serial No. 418,539. (No model.)

To all whom it may concern:

Be it known that I, JOSEPH J. BRENK, a citizen of the United States, and a resident of Milwaukee, in the county of Milwaukee, and 5 in the State of Wisconsin, have invented certain new and useful Improvements in Match-Safes; and I do hereby declare that the following is a full, clear, and exact description thereof.

10 My invention relates to new and useful improvements in match safes, and consists in the matters hereinafter described and pointed out in the appended claims.

In the accompanying drawings illustrating 15 my invention:—Figure 1. is a perspective view of a match safe embodying one form of my invention, showing parts broken away. Fig. 2. is a view of one of the blanks from which this form is made.

20 In said drawings:—A indicates a vertical magazine or holder, open at its lower end, and B a receiver or hopper communicating with the open lower end of the magazine A.

C indicates a box of matches placed on end 25 within the magazine A, and having the tubular cover C' partly withdrawn so as to open the lower end of said box.

The operation of my improved device will be readily understood by reference to the 30 drawings.

A box of matches is placed on end within the magazine or holder A, the tubular cover being partly withdrawn. The matches will then escape from the open lower end of the 35 box into the receiver or hopper B, from which they may be removed as required by the user. In this manner, an entire box full of matches may be placed within the match safe, and only comparatively few matches at a time 40 will be fed into the hopper B, the remainder being held within the box inside of the magazine A, in such a position as to automatically feed from the box into said hopper as fast as the matches are used therefrom.

45 If desired, the matches may be placed in the vertical magazine loosely, instead of being retained in the boxes as just described, but my device will be found very convenient for filling the match safe with an entire box 50 of matches at a time.

The blanks from which this form of my de-

vice is constructed may be made from any suitable or desired material, such for instance as sheet metal, paper or card-board. When made from sheet metal, a portion, such as the 55 front part b of the hopper B, is preferably roughened or corrugated, and when made from paper or card-board, said portion is preferably sanded, so as to afford convenient means for igniting the matches. As shown 60 at a, the rear wall of the holder may be perforated for convenient suspension from the wall.

As shown in Fig. 2 of the drawings, the blanks from which my improved match safes 65 are made, are preferably formed from a single piece of material, having a practically rectangular main portion, E, a practically rectangular side extension, F, of less depth than said main portion, a straight-edged 70 lower neck or extension, G, of less width than said main portion, and a lower extension, H, wider than said neck and main portion, and having oblique or angular ends or side terminations, I, I, the said blanks being preferably scored as indicated by the dotted lines 75 to facilitate bending at the proper points, and the tongues D D may be provided upon the margins of said blanks at suitable points, said tongues being arranged to engage with apertures or slots D' D' formed in the blanks so as to afford convenient means for securing 80 said margins in position by simply bending or clinching said tongues through said apertures or slots, when the blanks are made from 85 sheet metal, although solder may be applied if desired.

When the blanks are made from paper or card-board, the edges or tongues are conveniently gummed together.

If desired, my improved match safes may be packed for shipment in a knock-down condition and may be readily bent up and secured in proper position by the dealer or the user.

Having thus described my invention, what I claim as new, and desire to secure by Letters Patent of the United States, is—

1. A match-box blank composed of a single piece of material having a practically rectangular main portion, a practically rectangular side extension of less depth than said main 90

portion, a straight-edged lower neck or extension of less width than said main portion, and a lower extension wider than said main portion, and having oblique or angular ends or side terminations, substantially as set forth.

2. A match-box composed of a single piece of material, having a practically rectangular main portion, and a practically rectangular side extension, forming the main chamber, a straight-edged lower neck, forming the bottom, and a lower extension wider than said main portion and having oblique or angular ends or side terminations, forming the lower

open receptacle, the said piece being scored, folded, and held together by tongues or projecting edges on one folded part secured to the adjacent folded part, substantially as set forth.

In testimony that I claim the foregoing I have hereunto set my hand, at Milwaukee, in the county of Milwaukee and State of Wisconsin, in the presence of two witnesses.

JOSEPH J. BRENK.
